HERBERT C. WILLIAMSON AND BUFORD M. STUBBLEFIELD, OF YOUNGSTOWN, OHIO.

ROTARY GRIZZLY SCREEN.

Application filed April 29, 1927. Serial No. 187,460.

Our invention relates more particularly to that class of screening devices known as grizzly screens and which are in common use in various industries. These screens comprise a plurality of spaced parallel shafts on each of which is mounted a plurality of disks which, taken as a whole, form a bed over which the material to be screened is gradually carried as the shafts are rotated.

It has heretofore been usual to form each disk as a solid integral unit and to provide it with a central aperture for the passage of shaft on which it is to be disposed. The disks are then assembled on their respective shafts by slipping them one at a time over the end of the latter until the requisite number have been placed thereon and are then secured in position by suitable means operative to prevent them from moving longitudinally on the shaft. To insure the rotation of the disks in correspondence with the shaft the latter is frequently squared and the apertures in the disks correspondingly formed, or other suitable means employed to bring about this result.

This method of forming and assembling the disks on the shafts is open to the disadvantage, among others, that if at any time it is desired to remove one of the disks and replace it with a new one it is necessary to first unlock or remove the means by which the disks are held endwise on the shaft and to then take off all of the disks which lie between the end of the shaft and the disk which is to be replaced before the latter can be removed. Similarly, after the new disk is slid into position along the shaft all of the other disks which have been removed must be likewise replaced one at a time and the locking means then secured in position, all of which requires a considerable expenditure of time and labor as well as the risk of breaking some of the disks during the process of removing and replacing them on the shaft. Additionally, it is frequently necessary to remove the shaft from its bearings in the machine so as to permit the disks to be slid off the end of the shaft. Thus, not only does the actual labor cost of replacing a worn or broken disk amount to a considerable item but the time during which the machine is necessarily kept idle for that purpose materially reduces its maximum productive capacity.

An object of our invention therefore is to overcome the aforesaid disadvantages which

are inherent in the use of solid disks by providing disks which may be readily initially assembled on the shaft even though the latter be disposed in its bearings, and which may thereafter be individually or selectively removed and replaced without the necessity of removing any of the other disks in the assembly and, in fact, without the necessity of materially disturbing the position of the other disks on the shaft or removing the latter from its bearings.

Other novel objects and advantageous features comprehended by our invention are hereinafter more fully set forth or will be apparent from the following description of certain forms of our invention as illustrated in the accompanying drawings.

Generally speaking our invention comprehends the formation of each disk in two similar complementary parts separable on a diameter of the disks and the provision of means operative to temporarily hold the disks on the shaft as they are being initially assembled thereon or when one or more disks are being removed and replaced from the assembly in association with means adapted to force the disks longitudinally together so as to permanently maintain them in operatively assembled relation as will hereinafter be more fully explained.

In the accompanying drawings we have shown two slightly different embodiments of our invention, the first in Figs. 1 to 5 inclusive and the second in the remaining figures. More particularly, Fig. 1 is a somewhat fragmentary view of two adjacent shafts of a grizzly screen removed from the rest of the machine and each carrying a plurality of our improved disks in operatively assembled position, portions of certain of the disks being broken away to more clearly illustrate details of construction; Fig. 2 is an enlarged end view of one of the disks removed from the shaft; Fig. 3 is a side view thereof partially broken away to the plane of the line 3-3 in Fig. 2; Fig. 4 is an enlarged end view of one of the collars employed at each end of the series of disks on the shaft, and Fig. 5 is a side view of the collar partially broken away into central section. Figs. 6 to 8 inclusive, illustrate as stated a slightly different form of the invention and respectively generally correspond to Figs. 1 to 3 inclusive. Figs. 9 and 10 and Figs. 11 and 12, respectively generally corresponding to Figs. 4 and 5, respectively illus-

trate the two types of end collars adapted for employment in this form of the invention. The same numerals are used to designate corresponding parts in the several figures.

Referring now more particularly to that form of the invention shown in Figs. 1 to 5 inclusive it is to be primarily understood that all of the disks are of similar construction and that as many of them may be disposed on each shaft as may be desired in accordance with the particular size and requirements of the screen. The shafts 1 on which the disks 2 are supported are usually arranged in parallel relation and will generally be of circular cross section at their extremities to facilitate their support in suitable bearings (not shown). The central portion of each shaft, however, in the region in which the disks are disposed, may preferably be of square cross section with its corners slightly chamfered off and the central apertures of the disks are arranged to conform thereto and form a snug fit thereon.

Each disk comprises two similar complementary halves or sections, separable on a plane coincident with a diameter of the disk, and which when placed together form the complete disk. The latter considered as a whole comprises a central hub 3 having end faces 4, 4, and a peripheral flange 5 disposed equidistantly therefrom and, as hitherto stated, is provided with a transversely extending aperture 6 at its center conforming in shape and size to the squared region of the shaft so that the latter can extend snugly through it; conveniently the plane of division or separation between the sections, as indicated by the line 3-3 in Fig. 2, may extend at right angles to one of the flattened sides of the aperture 6.

For the purpose of holding the sections of the several disks temporarily together as they are being assembled on the shaft as well as for holding them in mutually locked relation after assembly, we provide each disk with means adapted to interengage corresponding means on the adjacent disks in such manner that the disk sections will be held together as they are progressively applied to the shaft during assembly thereon and will also, through the operation of any suitable locking means adapted to crowd the disks longitudinally together after they are assembled on the shaft, be locked together so as to form an operative non-relatively movable unit.

While said means may partake of various forms a satisfactorily operative embodiment thereof may comprise, as shown in the particular form of the invention to which reference is now being made, a rib 7 extending diametrically across the face 4 at each end of the hub 3 of the disk and projecting outwardly therefrom, the cross sectional con-

tour of the rib preferably conforming to the vertical section of a truncated pyramid. Preferably these ribs are disposed symmetrically with respect to the plane of separation of the sections of the disk so that one-half of each rib will lie on each side of the said plane when the sections are placed together. For the reception of the ribs on the adjacent disks, each disk is also provided with a pair of diametrically extending grooves 8, 8 respectively formed in the end faces 4, 4 of the hub and disposed at right angles to the ribs 7, 7, the grooves of course corresponding to the ribs in cross sectional form and size.

Any suitable means are also provided for forcing the disks longitudinally together after assembly on the shaft, for example, keys 10, 10 respectively adapted to be received in slots cut through the center of the shaft adjacent each end of the series of disks, each slot and each key having an inclined face or wall adapted for mutual cooperation in such manner that when the keys are driven into the slots they will exert a wedging action inwardly in opposite directions on the series of disks disposed between them. The keys may be held in adjusted position by set screws 11 or in any other suitable way.

To provide a suitable bearing at each end of the series of disks for the key or other means by which the disks are crowded together and locked into position we may utilize a solid collar, generally designated as 12, and best shown in Figs. 4 and 5. Each of these collars may have its inner face, that is, the face which is intended to lie next to the disks, provided with a diametrically extending rib 7' similar to the rib 7 on the disks and with a diametrical groove 8' disposed at right angles to the rib 7' and also similar to the grooves 8, while its outer face 13 may be plane, the collar of course being provided with a central squared aperture 14 similar to the aperture 6 and adapted to receive the squared portion of the shaft.

When constructed substantially in the manner described, the disks may be conveniently assembled in the shaft as follows, although other methods may be employed if desired: One of the collars 12 is first slipped over the end of the shaft with its ribbed face directed inwardly and slid along the shaft until its outer or plane face 9 passes the slot provided for the reception of the key; the latter is then inserted and temporarily secured in place so as to form a backing for the collar. The two sections of the first disk are then placed on opposite sides of the shaft, brought together about the same clear of the collar and then slid slightly along the shaft toward the collar until the ribs on the latter are seated in the groove in the adjacent face of the disk and the ribs on the disk correspondingly seated in the

groove in the collar. Under some circumstances it may be found more convenient instead of bringing the halves of the disk together at a point a little remote from the 5 collar and then sliding the disk into engagement therewith as just described, to simply engage the inner ends of the ribs on the halves of the disk in the outer ends of the grooves of the collar and then move the 10 halves of the disk radially inward against the shaft. However, whichever method be adopted, as soon as the first disk is in proper position, the sections of the next disk are applied to the shaft in a generally corresponding 15 manner, but with the plane of separation between the sections at right angles to the plane of separation between the sections of the first disk as best shown in Fig. 1. In like manner the sections of the 20 other disks are then progressively applied to the shaft and brought into engagement with the disks already disposed thereon, the planes of separation between the halves of the several disks being alternately disposed at 25 right angles to each other. During this process, by reason of the inter-engagement of the ribs and grooves upon the several disks the sections of the latter are held together on the shaft and prevented from separating 30 and falling off of the shaft until the required number of disks has been disposed thereon. When this is accomplished the other end collar is slipped into place over the end of the shaft so as to properly engage the end 35 face of the hub of the last of the series of disks and the adjacent key or other locking means inserted in the slot and driven into place, thus crowding all of the disks and collars together longitudinally and 40 forming them and the shaft into a rigid operative unit.

If at any time it be desired to remove one of the disks from the assembly, it is only necessary to loosen one or both of the wedges 45 enough to permit the disks to be pried longitudinally apart for an amount sufficient to enable the ribs and grooves or other inter-engaging means on the selected disk to be disengaged from the disks lying on each 50 side of it so that the halves of the selected disk may be separated and lifted off the shaft, all of the other disks meanwhile remaining thereon. A new disk may now be placed in position and the series of disks 55 again forced together longitudinally and locked in position by means of the wedges or other locking means.

In the form of the invention shown in Figs. 6 to 12 inclusive, we provide a slightly 60 different form of inter-engaging means for holding the disks together, said means comprising an annular rib 15 on one of the end faces 4 of each disk hub 3 and a corresponding annular groove 16 on the opposite end 65 face of the hub, both rib and groove pref-

erably conforming in cross section to the vertical section of a truncated pyramid. This type of inter-engaging means necessitates the employment of different forms of collars at opposite ends of the series of disks instead of similar collars as in the form of the invention hitherto described. Thus, a collar suitable for use at that end of a series of disks at which the end face of the last disk is provided with a groove is shown in 70 Figs. 9 and 10, the collar, generally designated as 17, having an annular rib 18 on its inner face adapted to seat in the corresponding annular groove in the adjacent disk and a plane outer face 19 adapted to be engaged by 75 the wedge or other locking means together with a central aperture 20 of suitable size and configuration to receive the shaft. A collar suitable for use at the opposite end of the series of disks is shown in Figs. 11 and 12; 80 this collar, generally designated as 21, having like the collar just described, a plane face 22 adapted for engagement by the wedge or other locking means, an annular groove 23 in its opposite face adapted to receive the annular rib 15 on the adjacent disk and a central aperture 24 for the passage of the shaft. The method of assembling this form of the invention and of selectively removing or replacing a disk from 85 the series corresponds generally to that heretofore described and will be readily apparent without additional explanation.

While we have herein illustrated and described certain forms of our invention with considerable particularity we do not thereby desire or intend to confine ourselves thereto nor to the use of any particular form of means for holding the disks in inter-engaged 90 relation as we believe it to be distinctly novel in the general class of screens to which our invention relates to utilize separable disks in combination with some form of means for holding the sections thereof together while the disks are being assembled 95 on the shaft or selectively removed and replaced, and we thus intend to claim our invention broadly without limiting ourselves to any precise details of design, construction and arrangement of the various parts or to the use of any particular means and instrumentalities for effecting the inter-engagement 100 of the disks.

Having thus described our invention, we claim and desire to protect by Letters Patent 105 of the United States:

1. In a grizzly screen or the like, a shaft and a series of disks disposed on said shaft, each of said disks being formed in two similar complementary sections and embodying means on each of its end faces inter-engaging complementary means on the adjacent disks to hold the sections of the disk together on the shaft.

2. In a grizzly screen or the like, a shaft 130

and a series of disks disposed thereon, each of said disks being formed of a pair of similar complementary sections the plane of separation between the sections coinciding with a 5 diameter of the disk, and means on the end faces of each disk inter-engaging complementary means on the end faces of the adjacent disks to hold the sections of the disk together on the shaft, the planes of separation of the sections of adjacent disks being disposed at right angles to each other.

3. In a grizzly screen or the like, a shaft and a series of disks disposed thereon, each disk in the series being formed in two similar 15 complementary sections separable on a plane coincident with the diameter of the disk and the end faces of each disk being provided with inter-engaging means respectively cooperative with complementary 20 means on the adjacent disks to hold the sections of the disks together on the shaft when the disks are thereon arranged with the planes of separation between the sections of adjacent disks disposed at right angles to 25 each other, and means operative to crowd the disks longitudinally together in assembled relation.

4. In a grizzly screen or the like, a squared shaft and a series of disks disposed thereon, 30 each of the disks in the series comprising a pair of similar complementary sections separable on a plane coincident with a diameter of the disk and having on its end faces means adapted for inter-engagement with 35 complementary means on the adjacent disks to hold the sections of the disks together on the shaft as they are progressively assembled thereon with the planes of separation of the sections of the disks arranged alternately 40 at right angles to each other, a collar at each end of the series of disks having means on its inner face cooperative with the inter-engaging means on the end of the adjacent disk, and means exterior of the collars operable to crowd the collars and disks together 45 longitudinally.

5. A grizzly screen disk having a hub apertured for the passage of a shaft, a peripheral flange extending from the hub and 50 means on the ends of the hub respectively

adapted for inter-engagement with complementary means on the adjacent disks, said disks being formed in two sections separable on a plane coincident with a diameter thereof.

6. A grizzly screen disk comprising two similar complementary sections which when placed together form the complete disk and having a hub apertured for the passage of a shaft and means on each end face of the hub adapted to inter-engage with complementary means on the hubs of adjacent disks and operative when so engaged to hold the sections of the disks together when the plane of division between said sections is disposed at right angles to the planes of division of the adjacent disks.

7. A grizzly screen disk formed in two similar, separable complementary halves and comprising an apertured hub, a diametrically extending rib on each end face of the hub and a diametrically extending groove in each said end face disposed at right angles to the rib and conforming in cross sectional contour thereto.

8. A grizzly screen disk formed in two similar, separable complementary halves and comprising an apertured hub, a diametrically extending rib on each end face of the hub divided longitudinally by the plane of separation between the halves of the disk and a diametrically extending groove in each said end face disposed at right angles to said rib.

9. A grizzly screen disk formed in two similar, separable complementary halves and comprising an apertured hub, a diametrically extending rib on each end face of the hub in cross section approximating the vertical section of a truncated pyramid, the center line of said rib coinciding with the plane of separation of the halves of the disk, and a diametrically extending groove formed in each said end face extending at right angles to the rib and conforming in cross section thereto.

In witness whereof, we have hereunto set our hands this 27th day of April, 1927.

HERBERT C. WILLIAMSON.
BUFORD M. STUBBLEFIELD.
